[57] CLAIM

The ornamental design for a combined telephone set and microprocessor, as shown and described.

DESCRIPTION

FIG. 1 is a top plan view of a combined telephone set and micro-processor showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof with the handset being separated from the housing for purposes of disclosure.

The wire is fragmentarily shown in FIGS. 2, 5 and 6 for convenience of illustration.
